ELECTRIC HEATER FOR WINDSCREENS AND WINDOWS

Filed Sept. 18, 1946

Inventor:
Cecil Robert Hopkins
By: *[Signature]*
Attorney

1. A heating device for use in association with a windscreens or windows, comprising a casing having a passage through which heat is directed upwards from the casing along the surface of the windscreens or windows, the air heated in this way, rising over the surface, draws with it cool air from below so that a stream of warm air will pass upwards between the casing and the surface and will safeguard the windscreens against damage from local overheating such as might be caused by hot air and rays directed with excessive intensity upon the surface in proximity to the casing.

This invention relates to electric heaters for use in association with windscreens and windows, especially the windscreens of motor road vehicles although also windscreens and windows in general, for preventing the formation of mist, frost or ice on the surfaces of the windscreens or windows or for the removal of mist, frost or ice from such surfaces. Hereinafter and in the appended claim windscreens and windows are called "windscreens."

More particularly, the invention relates to electric heaters as aforesaid of the type comprising a casing and an electric heating element extending within the casing from end to end thereof, the casing having a passage through which radiant heat is directed upwards from the casing along the surface of the windscreens to be warmed. The air heated in this way, rising over the surface, draws with it cool air from below so that a stream of warm air will pass upwards between the casing and the surface and will safeguard the windscreens against damage from local overheating such as might be caused by hot air and rays directed with excessive intensity upon the surface in proximity to the casing. Electric heaters of the type stated do not require the use of thermostatic or other control means to reduce or cut-off the supply of current to the element and they obviate all need for sub panels or other obstructive intermediaries that are provided in other heaters not of the type stated to absorb the heat radiated by the heater and spread it over the surface to be warmed.

Heaters of the type stated are supplied with current at low voltage. For instance, in the case of motor road vehicles the voltage as a rule does not exceed 12 volts, the current in each case being drawn from the battery circuit of the vehicle.

An object of the invention is to provide a heater of the type stated that extends over the width of the windscreens and has a low-voltage element of the requisite length and heating efficiency.

Another object is to provide a heater of the type stated having a heating element that consists of a ribbon-like resistance close-coiled so that the adjacent convolutions come sufficiently close to one another to radiate effectively on one another and thus maintain a heating zone of sufficiently concentrated intensity to set up the required flow of heated air.

Another object, in order that the heater may be suitable for windscreens of different widths, is to provide a casing that is of telescopic construction so that it is extensible to different sizes

ELECTRIC HEATER FOR WINDSCREENS
AND WINDOWS

Attala Cecil Robert Hopkins, Glasgow, Scotland.

Application September 18, 1946, Serial No. 697,700

1 Claim. (Cl. 219—19)

1. A heating device for use in association with a windscreens or windows, comprising a casing having a passage through which heat is directed upwards from the casing along the surface of the windscreens or windows, the air heated in this way, rising over the surface, draws with it cool air from below so that a stream of warm air will pass upwards between the casing and the surface and will safeguard the windscreens against damage from local overheating such as might be caused by hot air and rays directed with excessive intensity upon the surface in proximity to the casing.

The invention will now be more particularly described with reference to the accompanying sheet of drawings in which:

Fig. 1 is a front elevation of a heater of telescopic construction. Fig. 2 is an end elevation of the heater in the direction of arrow II of Fig. 1. Fig. 3 is a section to a larger scale on the line III—III of Fig. 1. Fig. 4 is a section on the line IV—IV of Fig. 1 to the same scale as Fig. 3. Fig. 5 is a large scale view of the close-coiled ribbon-like heating element.

Fig. 6 is a fragmentary view of another form of telescopic casing. Fig. 7 is a section to a larger scale on the line VII—VII of Fig. 6.

Fig. 8 is a fragmentary front elevation showing attachment means for mounting the heater on framework associated with the windscreens.

Fig. 9 is a fragmentary rear elevation corresponding to Fig. 8.

Referring particularly to Figs. 1 to 5, in this example the casing consists of an intermediate inner tube 1 about 2 feet long and terminal outer tubes 2 of slightly larger diameter, the arrangement being such that by sliding the tubes 2 telescopically along the tube 1 against the tension of the close-coiled ribbon-like heating element 3, the width across which the heater is effective may be modified to suit windscreens of different sizes. The tubes are made of a metal or alloy having good heat-conducting qualities. In order to ensure that the tubes cannot come apart the tube 1 is provided at its ends with lugs 4 which engage with inwardly projecting lips 5 on the relative ends of the tubes 2. The tubes 1 and 2 are each formed with a long narrow slot, about $\frac{1}{4}$ inch in width, and these slots form a continuous open passage which extends practically throughout the length of the casing (see Fig. 1). Radiant heat is directed upwards through the passage on to the surface to be heated at an inclined angle as indicated by the arrow A in Fig. 3.

The heating element 3 consists of a long ribbon-like coil of appropriate resistant alloy, the coil material being oblong in cross-section. The coil is supported at intervals throughout its length by thick washers 6 which fit neatly into the casing and which are composed of electricity-insulating refractory material.

In the example according to Figs. 1 to 5, at each end of the casing there is attached a suction cup 7, each cup being provided with an attachment screw 8, connected to a lug 9 which is a terminal extension of the associated tube 2. A nut 10

made of heat-insulating material serves to secure the screw and lug together. A washer 11 of similar material is interposed between the lug and the suction cup.

In the foregoing example the heater may be readily attached and detached from the surface to be warmed. Figs. 8 and 9 illustrate a method of more permanent attachment. A rod 12 is provided with a ring 13 which fits neatly upon the casing end, there being interposed between the ring and the casing a sleeve 14 of electricity-insulating refractory material. The foot of the rod is screwed at 15 for appropriate attachment say to a part 16 of the dashboard of the vehicle by nuts 17, 18.

Fig. 9 shows the terminal 3A at one end of the heating element 3, said terminal being a screw electricity-insulated by a ferrule 3B from the tube 2.

An alternative form of telescopic casing is shown in Figs. 6 and 7. On the inside of each end of the inner tube 1 there is provided a brass clip 19 which is permanently attached to the tube 1 by riveting or other means. Each clip projects beyond each side of the slot in the tube 1 and is bent over to form lips 20 which engage over the rims of the tubes 2 so that the tubes may readily slide along one another, thus providing for adjustment of the length, or widthwise span, of the whole casing. Midway between the ends of the tube 1 is a ring 21 which fits neatly over the tube and acts as a buffer for the tubes 2 in the telescopically contracted position of the casing.

As Fig. 5 shows, the ribbon-like resistance 3 is closely coiled. The design is such that adjacent convolutions come close to one another in order to radiate effectively on one another and thus provide a source of concentrated heat. Heat rays from this source (arrow A, Fig. 3) radiating through the long narrow passage in the casing heat the air in a zone extending along the exterior of the passage. This heated air rises and, in rising, induces cool air to flow upwards between the casing and the windscreens or window. Thus, a stream of warm air flows upwards over the surface of the windscreens or window.

Current for the heater is drawn from say an electric battery circuit by leads 22, and the heater may be switched on and off by a switch 23 of any known type. In the example the switch is of a one-way type situated at one end of the heater, as illustrated in Fig. 2; alternatively, a two-way switch may be used, and the switch may be located at any convenient point in the leads.

The heater may be modified in various respects without departing from the invention. For example, although it is preferable that the casing shall be part-cylindrical (because the cylindrical form facilitates manufacture and is effective in heat conservation) it may be of other sectional form. For instance, the casing may be angular or polygonal in cross-section, in which event the interior of the casing presents flat reflecting surfaces behind the element, instead of a circular reflecting surface as in the example. The casing need not be made of a metal or alloy; it could be made for instance of appropriate thermosetting plastic material in which event there may be no need to make provision for heat insulation or electricity insulation between the ends of the casing and its mountings. The passage for heated air need not be constituted as a single uninterrupted slot; there may be two or more slots or a series of holes spaced apart.

I claim:

A heater of the type stated comprising a casing consisting of a plurality of parts in telescopic relationship, which parts are extensible to vary the effective heating length of the casing, means limiting the extent of extensibility of said parts, a slot in each of said parts providing a continuous open passage extending lengthwise of the casing, and a heating element arranged in said casing alongside said passage and consisting of a ribbon-like resistance close-coiled so that the adjacent convolutions come sufficiently close to one another to radiate effectively on one another and thus provide a source of concentrated heat which acts through said passage to maintain a heating zone along the exterior thereof.

CECIL ROBERT HOPKINS.
